CLAIM

The ornamental design for an ornament, as shown and described.

DESCRIPTION

FIG. 1 is a front perspective view of an ornament showing my new design;

FIG. 2 is a rear perspective view thereof;

FIG. 3 is a front elevation view thereof;

FIG. 4 is a rear elevation view thereof;

FIG. 5 is a side elevation view thereof;

FIG. 6 is a top plan view thereof; and,

FIG. 7 is a bottom plan thereof.

The broken lines in the drawings depict environmental subject matter only and form no part of the claimed design.
